US00D424453S

United States Patent [19]

Atterbury et al.

[11] Patent Number: Des. 424,453

[45] Date of Patent: ** May 9, 2000

[54] DETECTOR UNIT FOR RADIATION
DETECTING PROBE

[75] Inventors: **William G. Atterbury**, Columbus;
James E. Dvorsky, Hilliard; **Beth A. Gahagan**; **Donald J. Hackman**, both
of Columbus; **Daniel A. Kramer**,
Dublin, all of Ohio

[73] Assignee: **Neoprobe Corporation**, Dublin, Ohio

[**] Term: **14 Years**

[21] Appl. No.: **29/067,947**

[22] Filed: **Mar. 18, 1997**

[51] LOC (7) Cl. **10-04**

[52] U.S. Cl. **D10/47**

[57] CLAIM

The ornamental design for detector unit for radiation detecting probe, as shown.

DESCRIPTION

FIG. 1 is a side elevational view of the detector unit for the radiation detecting probe showing my new design, the opposite side being identical thereto;

FIG. 2 is a top plan view thereof;

FIG. 3 is a bottom view thereof;

FIG. 4 is front view thereof; and,

FIG. 5 is a rear view thereof.

The broken line showing is for illustrative purposes only and forms no part of the claimed design.
